[57] **CLAIM**

The ornamental design for a combined checkstand and control cabinet assembly, as shown.

DESCRIPTION

FIG. 1 is a perspective view of a combined checkstand and control cabinet assembly embodying my design;

FIG. 2 is a top plan view thereof;

FIG. 3 is a side elevational view of the checkstand taken from the right of FIG. 1;

FIG. 4 is a side elevational view of the checkstand taken from the left of FIG. 1;

FIG. 5 is an elevational view of the checkstand taken from the front of FIG. 1;

FIG. 6 is an elevational view of the control cabinet taken from the front of FIG. 1;

FIG. 7 is an elevational view of the control cabinet taken from the right of FIG. 1;

FIG. 8 is an elevational view taken from the rear of FIG. 1;

FIG. 9 is an elevational view taken from the left of FIG. 1.
